UNITED STATES PATENT OFFICE.

THOMAS A. COLE, OF INDIANAPOLIS, INDIANA, ASSIGNOR, BY DIRECT AND MESNE ASSIGNMENTS, TO THE AMERICAN MANUFACTURING COMPANY, OF SAME PLACE.

CIGAR-TIP CUTTER.

SPECIFICATION forming part of Letters Patent No. 606,377, dated June 28, 1898.

Application filed October 25, 1897. Serial No. 656,248. (No model.)

To all whom it may concern:

Be it known that I, THOMAS A. COLE, a citizen of the United States, residing at Indianapolis, in the county of Marion and State of Indiana, have invented certain new and useful Improvements in Cigar-Tip Cutters; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to cigar-tip cutters of that class that are adapted to clip the tips from cigars preparatory to lighting them and that in connection therewith display a series of advertising-cards and announce a premium 20 whenever a predetermined number of cigars have been clipped.

The objects of my invention are, first, to provide a cigar-tip cutter of the class described that will be novel and attractive in 25 appearance; second, that will remain locked, so that it cannot be operated until a cigar-tip is placed within one of the apertures in the front of the case; third, that may be unlocked and rendered operative when a cigar-tip is 30 placed in one of the apertures in the front of the case and the lever below said aperture depressed; fourth, that will simultaneously with its operation throw into view an advertising-card above the lever operated and at the same 35 time cause the advertising-card just previously displayed to disappear; fifth, that will automatically sound an alarm when a predetermined number of cigars have been clipped for the purpose of notifying the purchaser 40 that a premium is due; sixth, to provide in a cigar-tip cutter of that class a means for alternately locking the operating-levers against being raised from the outside after each operation, and, seventh, to provide a cigar-tip 45 cutter in which the clipping mechanism, advertising-display cards, and premium-announcing device are adapted to be actuated by means of the operation of said operating-levers.

With these objects in view my invention 50 consists in the construction and combination shown in the accompanying drawings and described in the following specification.

In the drawings, Figure 1 is a perspective view of my improved cigar-tip cutter. Fig. 2 55 is an end elevation of the same with the end of the case removed. Fig. 3 is a side elevation of one of the operating-levers, showing the details of its construction. Fig. 4 is a front elevation of the working parts with the 60 front and top of the case removed. Fig. 5 is a top plan view of the working parts with top of case removed. Fig. 6 is an enlarged fragmentary view showing the construction of the lever-locking device. Fig. 7 is a side elevation 65 of one of the advertising-card-lifting levers, and Fig. 8 is a top plan view of the same. Fig. 9 is a longitudinal sectional view taken through the center of one of the clipping-knives.

Referring to the drawings, the case is composed of the ends 1, the front 2, having lever-slots 3, the top 4 and 5, the back 6, the card-rack 7, and the bottom 8. These various portions of the case are suitably secured together 75 by means of screws or in any other desirable manner. The top portion 4 is rounded throughout its length in the center to conform with the clipping-knives and has a series of large and small openings 9 to receive the cigar-tips. The top portion 5 has a series of slots near its rear edge, in which the movable card-holders slide up and down. The card-rack 7 is provided with a series of openings 10, within which advertising-cards are adapted 80 to be placed. A sliding lever-locking bar 11 is adapted to slide against the front portion 2 at the lower edge of the slots 3. L-shaped notches 12 are cut in the upper edge of said bar opposite the slots 3 for the purpose of receiving the operating-levers 13 when they are depressed, said levers each having a rib 14 along their sides, which engage with the projection 15 on the bar 11, so that their 85 points 12^a extend slightly beyond the point of the projection 15 of said bar. The object of this projecting point is to cause the bar 11 to 90 95

slide slightly farther than the shoulder 15 would permit it to slide when one of the levers 13 is depressed, thereby releasing the lever previously depressed without friction. In Fig. 6 the dog is shown raised, as when the lever 13 is being raised, its normal position, however, being indicated by the dotted lines in the same figure. Said slide-bar 11 rests upon lugs 17 and is secured against the front 10 by means of screws 18, passing through slots 19. The bar 11 is held normally in the position shown in Fig. 6 by means of a coil-spring 20, located within the case and adapted to bear against the lug 21, secured to the end of 15 said bar, as seen in Fig. 5. A series of supporting-brackets 22, 23, 24, and 25 are secured to the bottom 8 and form bearings for the shaft 26, mounted thereon. On the inner edges of the ends 50 are notches 58, which allow the clipper to bear against the top 4 as soon as it has passed the lug 51, thereby making a clean cut when it engages the cigar-tip. The clippers 48 have an opening 53 at their rear end, which receives a coil-spring 54, the 25 other end of which is attached to the projecting portion 35. Another larger coil-spring 55 is secured at one end to said portion 35 and at the other to the bottom 8 of the case by staples 56.

30 In operation the cigar-tip is placed in an opening 9, striking the portion 50 of the clipping-blade and releasing it from the lug 51, thereby permitting the lever 13 to be pressed down, causing the blade to slide forward and the edge 52 to clip the cigar-tip, and at the same time causing the pawl 37 to engage the ratchet-wheel 27 and turn the shaft 26 slightly, and by reason of the connection of the lifting-levers 39 with the shoulder-pins 43 the 35 advertising-card holder 47 will be thrown up into view, temporarily hiding the fixed space 10 on the rack 7, which is behind it. The lever 13 is held in its depressed position by reason of the locking-bar 11, as above described, 40 until another cigar is clipped by one of the other levers, when it will be thrown up in its normal position by the coil-springs 54 and 55 and is again ready to be operated. The alarm-bell 33 is sounded by the striker 31, the striker 45 being actuated by the pins 30 on the disk 29. Should there be forty teeth on the ratchet-wheels 27, it will require the clipping of forty cigars to make one complete revolution of the shaft 26. Hence if there are four pins on the disk 29 the alarm will be sounded four times while the forty cigars are being clipped. To provide an easy way of regulating the sounding of the alarm, the pins 30 are of unequal 50 lengths, so that by sliding the collar 28 on the shaft 26 the number of pins 30 that will come in contact with the striker 31 during one revolution of the shaft can be easily changed without the necessity of removing or replacing the pins. A greater or less number of pins of unequal lengths may be used upon the disk 29,

thereby allowing a wide range in adjusting the alarm.

From the above description it will be seen that the alarm is only sounded by the rotation of the shaft 26 and that this rotation is effected by the depression of the levers 13, and as the levers can only be depressed by disengaging the ends 50 of the blades 48 from the lugs 51, which is done by inserting and clipping a cigar-tip, it is apparent that the alarms will not be sounded except by the actual clipping of cigars. The purpose of the alarm is to allow the merchant to offer as an advertisement a cigar free to the customer who, when clipping a cigar, causes the alarm to sound. The percentage of cigars to be given away is determined by the seller and is wholly under his control. The advertising-racks 47, which rise and fall with the operation of the levers 13, are adapted to carry 85 suitable advertising-cards, and the fixed rack 7 has the spaces 10, which are also adapted to receive advertisements. The racks 47 rise through slots in the top portion 5. It will be seen that wherever one of the levers 90 13 is depressed it becomes locked, while the lever just previously depressed is released and rises at once into operative position.

Having thus described my invention, what I claim, and desire to secure by Letters Patent of the United States, is—

1. The combination in a cigar-tip cutter of the class described, having a suitable inclosing case arranged with advertising-spaces, and a mechanism for displaying advertising-cards, of the clipping mechanism consisting of the levers 13, the shaft 26, the pivotally-mounted blades 48, and the locking-lugs 51, with the alarm-gong mechanism, which is adapted to be actuated by the operation of the levers 13, and the lever-locking bar 11, having the L-shaped notches 12 and the pivotally-mounted dogs 16, whereby the levers 12 are consecutively locked after each operation, substantially as shown and described.

2. In a cigar-tip cutter of the class described, having a suitable case provided with a series of openings to receive the ends of cigars to be clipped, an automatic alarm-sounding device, whereby the alarm is sounded whenever a predetermined number of cigars have been clipped, and a series of advertising-card racks adapted to be displayed consecutively whenever the clipping mechanism connected therewith, is operated, the combination of the clipping mechanism consisting of the spring-tensioned pivotally-mounted blades 48, having the cutting edges 52, adapted to slide against the under side of said case 4, opposite the openings 9, the levers, 13, having said blades 48 pivotally mounted upon their upper ends, and the shaft 26, suitably supported by brackets and carrying the levers 13, with the mechanism for successively locking said levers, consisting of a

slidably-mounted spring-controlled bar 11, having L-shaped notches 12 to receive the operating-levers 13, and shoulders 15, to engage the ribs 14 on the levers 13 and hold said levers when they are depressed, said bar 11 mounted within the front 2 of said case, all as shown and described.

In testimony whereof I affix my signature in presence of two witnesses.

THOMAS A. COLE.
